REMOTE POWERED CULINARY BEATER HEAD

Arthur W. Lambert, Morecambe, England

Application November 30, 1954, Serial No. 33,329

Term of patent 14 years

(Cl. D44—1)

Fig. 1 is a perspective view of a remote powered culinary beater head showing my new design;

Fig. 2 is an end elevational view thereof;

Fig. 3 is an elevational view of the end opposite that shown in Fig. 2;

Fig. 4 is a top plan view thereof;

Fig. 5 is a side elevational view thereof; and

Fig. 6 is a bottom plan view thereof.

I claim:

The ornamental design for a remote powered culinary beater head, as shown.
